UNITED STATES PATENT OFFICE

ZENO C. HABERMAN, OF WATERTOWN, SOUTH DAKOTA.

DESIGN FOR A WASHING-MACHINE CASING.

Application filed January 28, 1922. Serial No. 418. Term of patent 3½ years.

To all whom it may concern:

Be it known that I, ZENO C. HABERMAN, a citizen of the United States, residing in Watertown, county of Codington, and State of South Dakota, have invented a new, original, and ornamental Design for Washing-Machine Casing, of which the following is a specification, reference being had to the accompanying drawings, forming part hereof.

In the drawings:

Figure 1 is a perspective view of the front

and side of the washing machine casing showing my new design; and

Figure 2 is a view of the same washing machine casing in side elevation.

I claim:

The ornamental design for a washing machine casing as shown.

ZENO C. HABERMAN.
